UNITED STATES PATENT OFFICE.

DUDLEY E. MACKEY, OF BLOOMFIELD, AND FREDERICK L. BLACK, OF EAST ORANGE,
NEW JERSEY.

EXERCISING DEVICE.

Application filed July 13, 1928. Serial No. 292,564.

This invention relates to kinesitherapy, and the general object of the invention is to provide an improved device for exercising and developing the muscles of the 5 human body, reducing persons afflicted with obesity and curing muscular and other disorders, ailments and the like in a pleasant, easy and expeditious manner with very little or no work or exertion on the part 10 of the person using the device.

A further object of the invention is to provide a massaging and exercising machine that is capable of working on all parts of the human body and sets up a combined 15 massaging, rubbing, vibrating and slapping action which results in bringing about the desired development of the muscles, rapid decrease in fat tissues and parts, and cure of diseases with minimum use of the machine.

Another object of the invention is to provide a machine of the character set forth, that is relatively simple in construction, inexpensive to manufacture and efficient in operation and service.

This invention also consists in certain other features of construction and in the combination and arrangement of the several parts, to be hereinafter fully described, 30 illustrated in the accompanying drawings and specifically pointed out in the appended claims.

In describing our invention in detail, reference will be had to the accompanying 35 drawings therein like characters denote like or corresponding parts throughout the several views, and in which:

Figure 1 is a fragmentary side elevation of the machine forming the subject matter 40 of the present invention.

Figure 2 is a fragmentary front view thereof.

Figure 3 is a top plan view.

Figure 4 is a detail view of one of the 45 end plates which receives the belt and eccentric rollers.

Figure 5 is a similar view of the other side of the plate.

Figure 6 is a sectional view taken approximately on line 6—6 of Figure 4, looking 50 in the direction of the arrows.

Figure 7 is a fragmentary detail view showing one of the attaching ends for the belt.

55 Referring to the drawings in detail, the

reference numeral 1 indicates an electric motor formed with or secured to a base 2 which may be provided with a supporting frame 3 having legs suitably braced as suggested in Figure 1.

The armature shaft of the motor extends beyond the opposite ends thereof and secured to these ends by any well known means are eccentrically mounted rollers 4. One of the rollers 4 is mounted on each 60 end of the shaft and in a manner whereby the rollers project in opposed relation with respect to each other as clearly shown in Figure 3 of the drawings.

Rising from each end of the base 2 and centrally thereof are ears 5 arranged in pairs and formed with apertures adapted to receive pins which pass through the lower ends of end plates 6. The lower ends of the end plates 6 are reduced to be received between the pairs of ears as best shown in Figure 2, and these end plates are substantially V-shaped in formation with rounded upper ends, the plates being disposed so that the apexes thereof are secured to the pivot pins which are journaled in the ears 5 so as to allow the plates to be reciprocated in a manner which will be presently apparent.

The end plates 6 have formed in their 85 inner faces recesses 7 terminating in a rounded bottom and having straight side walls which merge into converging walls 8 at the tops of said recesses as best shown in Figure 5. These recesses 7 receive the eccentrically mounted rollers 4 for movement therein, and it will be apparent that when the motor is put into operation through the instrumentality of a switch 9 the end plates will be caused to reciprocate 90 in opposed relation with respect to each other due to the arrangement of the eccentrically mounted rollers 4, as the rollers engage the side walls of the recesses 7 for the purpose set forth.

Laterally extending from the outer sides of the end plates 6 adjacent the top and one end thereof are pairs of apertured ears 10 which have secured thereto through the medium of pivot pins the bearing end of arms 11. The opposite ends of the arms 11 are formed with openings to accommodate stem bolts 12 which have one of their ends threadedly secured in the plates while the opposite ends of the bolts 12 are threaded 100 105 110

for receiving thumb nuts 13 for the purpose of securing the arms in operative position as best shown in Figure 6.

Each of the end plates 6 have arranged therein a plurality of bores 14 formed in the outer surface thereof and disposed in row formation. The arms 11 are positioned to face the bores 14 when secured to the stem bolts 12 and are adapted to detachably secure in any one of the bores of each plate the end 15 of attaching members 16 which include flat portions riveted or otherwise secured to the ends of a belt 17. The ends 15 of the attaching members 16 are disposed 10 at right angles to the flat portions of the attaching members, with the result the side portions of the belt will be disposed accordingly with respect to the machine with the loop portion of the belt facing the motor, 15 and due to this arrangement as well as the arrangement of the switch 9, a person using 20 the machine can readily control the motor thereof as will be apparent.

From the above description and disclosure 25 of the drawings, it will be obvious that we have provided a massaging and exercising machine that is capable of being used on the human body for most any desired purpose, and due to the novel movement of the end 30 plates 6, by the engagement of the eccentrically mounted rollers 4 therewith, the belt will be given a combined massaging, rubbing, vibrating and slapping action, with the result the parts of the body in the path 35 of the belt will be worked upon accordingly. In the use of the machine the person or the part of the person desired to be worked upon is disposed whereby the inner surface of the belt engages the body of the person or part 40 and by pulling upon the belt, to the degree desired, the belt's action can be controlled with respect to the body of the person or parts thereof accordingly.

It is thought from the foregoing description 45 that the advantages and novel features of our invention will be readily apparent.

We desire it to be understood that we may make changes in the construction and in the combination and arrangement of the several 50 parts, provided that such changes fall within the scope of the appended claims.

What we claim is:

1. A machine of the character described 55 comprising a base, an electric motor supported by and secured to said base, eccentrically mounted rollers disposed in opposed relation with respect to each other and secured to the ends of the armature shaft of said motor, plates pivotally secured to said base and being recessed in their confronting faces to receive the rollers for reciprocating 60 said plates, and a belt having its ends adjustably secured to said plates.

2. A machine of the character described 65 comprising a base, an electric motor secured

to said base, rollers eccentrically mounted on the ends of the armature shaft of said motor and being secured to said ends in a manner whereby they are disposed in spaced relation with respect to each other, plates 70 pivotally secured to said base and being mounted for reciprocation, said plates having recesses formed in their confronting faces to receive said rollers, said plates being formed with bores arranged in row formation, a belt, means secured to the ends of said belt and being adapted to be received in any one of the bores of the plates, and means carried by said plates for detachably securing the belt carrying means in said 80 bores.

3. A machine of the character described comprising a base, a supporting frame therefor, an electric motor secured to said base, rollers eccentrically mounted on the ends of the armature shaft of said motor, ears rising 85 from said base and arranged in pairs, plates having reduced ends pivoted between said ears, said plates having recessed confronting faces to accommodate the rollers in a 90 manner whereby the plates are reciprocated in opposed relation with respect to each other by said rollers, said plates having bores arranged in row formation therein, a belt, attaching members formed with the 95 ends of said belt, means formed with the attaching ends and being adapted to be received in any one of said bores, and means carried by said plates for detachably securing the means of the attaching members in 100 said bores.

4. A machine of the character described comprising a base, an electric motor secured to said base, rollers secured to the ends of the armature shaft of said motor and being eccentrically mounted thereon in a manner whereby the rollers are disposed in opposed relation with respect to each other, substantially V-shaped plates mounted for reciprocation on said base and being recessed to 110 accommodate said rollers, a belt, attaching members secured to the ends of said belt, means formed with the attaching members and being adapted to be received in bores formed in the plates, and arms carried by 115 said plates for engagement with the attaching members to retain the means thereof in said bores, said arms having one of their ends pivotally secured to said plates and their opposite ends detachably secured thereto.

5. A machine of the character described comprising a base, an electric motor secured to said base, means mounted on said base for controlling said motor, means pivotally secured to said base and upon opposite sides of said motor, means operated by said motor for reciprocating the pivotally secured means in opposed relation with respect to each other, a belt, attaching members se- 130

cured to the ends of said belts, means formed with said attaching members and disposed at right angles thereto to be received in bores formed in the pivoted means, arms having 5 one of their ends pivotally secured to said pivotally secured means and their opposite ends detachably secured thereto, and said

arms being engageable with the means carried by the attaching members for securing the same in said bores.

10

In testimony whereof we affix our signatures.

DUDLEY E. MACKEY.
